US0D1089010S

(12) **United States Design Patent** (10) **Patent No.:** **US D1,089,010 S**
(45) **Date of Patent:** **** Aug. 19, 2025**

(54) **FENDER PANEL FOR VEHICLES**

(71) Applicants: **Hyundai Motor Company**, Seoul (KR); **Kia Corporation**, Seoul (KR)

(72) Inventors: **Byung-Ok Lee**, Gyeonggi-do (KR); **Hong-Seok Choi**, Gyeonggi-do (KR); **Kyung-Bum Kang**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/888,834**

(22) Filed: **Apr. 5, 2023**

(30) **Foreign Application Priority Data**

Nov. 14, 2022 (KR) 30-2022-0046917
